UNITED STATES PATENT OFFICE.

VICTOR DIONNE, OF LODI, CALIFORNIA.

TRACTOR.

1,184,083.

Specification of Letters Patent.

Patented May 23, 1916.

Application filed July 27, 1914. Serial No. 853,264.

To all whom it may concern:

Be it known that I, VICTOR DIONNE, a subject of Great Britain, residing at Lodi, in the county of San Joaquin, State of California, have invented new useful Improvements in Tractors; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in tractors and particularly to those propelled by explosive motors and to the means of applying the power to the wheels of said tractor. By means of the method herein set forth, a compact power saving arrangement is obtained thereby producing a machine with the least amount of wear of parts and most economical in operation.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a side elevation showing the rear wheel partly broken out. Fig. 2 is a plan view of the engine and gears as inclosed in each wheel. Fig. 3 is an elevation from the back showing one wheel broken out in section. Fig. 4 shows the draw-head and the manner of hanging the frame to the shaft. Fig. 5 is a side view of one wheel.

Referring now more particularly to the characters of reference on the drawings, the numeral 1 designates the frame of the tractor, the numeral 2 the front wheel thereof and the numeral 3 designates a steering wheel with a worm and gear, as at 4, connected to the front wheel 2 by means of a chain 5 or any other suitable steering arrangement, as desired.

Turnably mounted upon the rear axle 6 of the tractor is the downwardly projecting bracket 7 with a hub 8 and a flange portion

9, extending horizontally from the portion 7 is the member 10 forming a supporting means for the motor 11. Integral with the member 10 are the lugs 12 carrying rollers 13 turnably mounted upon pins 14 thereof and at the other extreme portion are lugs 15 carrying a shaft 16 upon which are mounted spur pinions 17. Turnably mounted on the shaft 16 are beveled gears 18 and 19 intermeshing with the driving keyed pinion 20 upon the end of the motor shaft 21. Interposed between the bevel gears 18 and 19 upon a feather in the shaft 16 is the jaw tooth clutch 22 moved by means of a lever, not shown, to obtain the forward and reverse motion in the usual common manner. Adjacent the bevel pinion 20 upon the shaft 21 of the motor is a friction clutch 22 for throwing the engine in or out of gear.

To the inside of the tire member 23 of the rear wheels I have fastened the annular internal gear 24 integral with which are supporting spokes 25 and an overlying ring 26 forming a track for the rollers 13 hereinbefore mentioned. The spokes 25 terminate in a hub 27 elongated as shown to form a suitable bearing for the axle 6 closed on its end, as at 28. The corresponding gear on the other side of the wheel is made the same except that the spokes 29 thereof terminate in a large annular hub 30 which on its inside periphery is V-shaped, as at 31, and is slidable in the groove formed by the flange member 9 of the bracket 7 and the flange 32. Integral with a hub 33 are arms 34 and 35 connected by transverse members 36 and 37 formed as shown in Fig. 4. The flanges 9 and 32 are held together by means of bolts 39.

The frame 1 is suspended from the hub 33 by means of a yoke 38 fastened as shown at 40, by which arrangement a slight rotatable movement is permitted upon the hub 33. Projecting from the hub 33 are arms 41 above the frame 1 and interposed between said members is a spring 42 through which I have placed a bolt 43 fastened in the arm 41 and the frame 1. By means of this arrangement I have provided a means for compensating for any jerking that may be communicated to the tractor through the arm 35 which I intend to use as a draw-head. This arm will also act as a lever in holding the engine down and as the power exerted by the engine will be increased with the weight of the pull the two forces will

compensate for each other and tend to hold the engine in a normal position thereby overcoming any climbing tendency.

Through the flanges 9 and 32 I have provided an opening 44 for the admission of all water pipes, lever leads, and carbureter and magneto controls. From the radiator 45 are pipes 46 and 47 admitted to the engine through the opening 44 and connected in the usual manner. To the lever 48 and corresponding levers not shown, are fastened the leads 49 and 49^a leading to the clutch 22 on the engine shaft 21 and the clutch 22^a on the cross shaft 16. To the outside of the wheels and fastened to the spokes 25 by means of bolts 51 are plates 50. Every other plate, as at 52, I have fastened by means of wing nuts 53 so that it may be readily removed and the engine thereby being made easily accessible. The inside of the wheel I have inclosed in the same manner by means of plates 54.

From the foregoing description it will readily be seen that I have inclosed all the principal working parts against the entrance of any dirt or dust thereby cutting down the resultant wear of the various members. The arrangement of the parts is compact, yet readily accessible, thereby allowing the greatest amount of room for carrying a load on the frame of the tractor.

From the foregoing description it will further be seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention as defined by the appended claims.

Having thus described my invention what I claim as new and useful and desire to secure by Letters Patent is:—

1. In a device of the character described a wheel, internal pinions on said wheel, annular rings within said wheel, a motor suspended independently of said wheel, rollers attached to one end of the motor and bearing on said annular rings, pinions attached to the other end of the motor and engaging such internal pinions on said wheel, and means for driving said pinions from the motor, as described.

2. In a device of the character described

the combination with an axle, of a hub bearing on the axle, a motor suspended from said hub, a wheel having a hub bearing on the axle, and means operable between the motor and the wheel for driving the wheel with the action of the motor, as described.

3. In a device of the character described the combination with an axle, of a hub mounted on the axle, a motor suspended on the hub, a wheel, a hub on the wheel mounted on the axle, one side of the wheel bearing around said first named hub, and means between the motor and the wheel for driving the wheel with the operation of the motor, as described.

4. In a device of the character described the combination with an axle, a hub mounted on the axle and provided with an opening, a wheel, a hub on the wheel mounted on the axle, one side of the wheel bearing around said first named hub, a motor suspended on the first named hub and adapted to operate the wheel, and connections for the motor projecting through said opening, as described.

5. A device of the character described comprising the combination with a tractor having a shaft, of a bracket turnably mounted on said shaft, a motor carried by said bracket and connected in driving relation with a wheel of said tractor, arms on said bracket and springs interposed between said arms and the body of said tractor, as described.

6. In a device of the character described the combination with an axle, spaced hubs turnably mounted on the axle and connected by cross members, a motor suspended from each hub, wheels having hubs mounted on the axle, each motor being arranged to drive one of said wheels, as described.

7. In a device of the character described the combination of an axle, spaced hubs mounted on the axle and connected by cross members, a bracket swung on each hub, a vehicle frame connected with said brackets, a motor suspended from each hub, and wheels arranged to be driven by said motors, as described.

In testimony whereof I affix my signature in presence of two witnesses,

VICTOR DIONNE.
